UNITED STATES PATENT OFFICE.

EDWIN D. SMITH, OF ST. LOUIS, MISSOURI.

RAIL-CROSSING.

1,251,123.

Specification of Letters Patent. Patented Dec. 25, 1917.

Application filed May 7, 1917. Serial No. 166,815.

To all whom it may concern:

Be it known that I, EDWIN D. SMITH, a citizen of the United States, residing at the city of St. Louis and State of Missouri, have 5 invented a new and useful Rail-Crossing, of which the following is a specification.

This invention relates to rail crossings.

The object of the invention is to provide an improved rail crossing in which the 10 flanged rails of the track are equipped with attached continuous risers for supporting the flanges of the car wheels passing over the crossing in such position that the treads of the wheels are continuously supported 15 between gage lines substantially out of contact with the upper surfaces of the rails, while the flanges of the wheels extend a sufficient distance below the upper surfaces of the rails to prevent derailment of the car.

Another object of the invention is to provide an improved rail crossing adapted especially for use by street railway lines and comprising intersecting rails each including a tread or body portion and a flange extending 20 obliquely inwardly and upwardly and forming a groove for the flanges of the wheels; in combination with risers attached to the flanges within the grooves of the rails respectively and each composed preferably of a manganese steel plate, said plates 25 continuously filling the grooves in the rails between gage lines and arranged to serve as treads for the flanges of the wheels to keep the treads of the wheels substantially 30 out of contact with the upper surfaces of the rails. The manganese steel plates are preferably formed with longitudinal grooves 35 in their inner surfaces and attached to the flanges of the rails by binding elements 40 outside of the wheel flange contact so that appropriate resiliency is obtained.

With the foregoing and other objects in view, I have produced a preferred embodiment of the invention and have illustrated 45 the same in the accompanying drawings in which—

Figure 1 is a plan view of a crossing constructed in accordance with my invention.

Fig. 2 is a sectional view on the line 2—2 50 of Fig. 1.

Fig. 3 is a side elevation of one of the crossing rails viewed approximately from the line 3—3 of Fig. 1.

Figs. 4, 5 and 6 are sectional views taken 55 on the lines 4—4, 5—5 and 6—6 respectively of Fig. 1.

Fig. 7 is a perspective view of one of the riser plates detached from the rails.

In the embodiment in which I have illustrated my present invention each rail comprises a tread or body portion 1 and a flange 2 curving obliquely upwardly and inwardly from the lower portion of the top and forming therewith a groove or channel in which the flanges of the car wheels operate. At 60 the intersection of the rails experience has demonstrated the desirability of supporting the treads of the wheels substantially out of contact with the tops or treads of the rails in order to prevent deterioration and 65 provide a smoother crossing.

In order to effect this desirable result, I have devised risers preferably in the form of manganese steel plates adapted to be attached to the flanges of the rails within the 70 grooves to receive the flanges of the wheels and support the wheels substantially out of contact with the tops of the rails, while at the same time permitting the flanges of the 75 wheels to operate a sufficient distance below the tops of the rails to prevent derailment of the cars passing the crossing. These plates are preferably in separate sections capable of independent attachment to the rails and the end sections thereof are designated by 80 85 3 which are tapering or inclined as clearly illustrated in Fig. 2, so that the flanges of the car wheels will mount and pass from the risers without perceptible jolt or jar. The intermediate portions of the risers are in the 85 90 form of separate plates 4, the upper surfaces of which serve as treads for the flanges of the car wheels passing the crossing thereby supporting the tires or treads of the wheels 95 substantially out of contact with the tops of the rails. The upper surfaces of the risers, however, are a sufficient distance below the tops of the rails to enable the flanges to 100 105 operate with the rails to prevent derailment of the cars as will be readily understood by reference to Figs. 4, 5 and 6 of the drawing.

Each of the riser plates 3 and 4 includes a part 5 shaped to conform to the groove in which it is placed, and also includes a part 6 extending obliquely-upwardly and inwardly to match the upper surface of the flange 2 of the rail upon which it is placed. The parts 6 are formed with longitudinal 110 grooves or channels 7 in their under sides so that when the risers are placed in longitudinal series upon the rails there is a longitudinal groove or channel between the risers and

the flanges of the rails. The several plates composing the risers are attached to the rails by rivets 8 passing through the flanges of the rails and through the parts 6 of the risers and also passing through the grooves 7. In this way the several plates are independently detachable so that when any one of them becomes defective or damaged from any cause it may be removed, and replaced 10 by another without interfering with any other part of the crossing. This is a material advantage over a construction in which the risers are integrally united with specially made crossing rails, since by my construction I am enabled to use at the crossing rails of the same construction as the rails composing the remaining portions of the track.

The provision of the grooves or channels 20 enables the riser plates to be fitted readily in position without the necessity of machining the matching surfaces of the plates and rails. The co-efficient of expansion and contraction of the riser plates, particularly if 25 they are constructed of manganese steel as is preferred, is different from that of the usual steel rails. Because of this difference, if the riser plates and rails are in contact throughout their adjacent surfaces, an undesired 30 separation of the side walls of the riser plates from the side walls of the grooves in the rails in which they are seated will result, as an incident to the considerable variations in temperature which occur in most localities 35 in which these crossings are used. As a consequence of the formation of the grooves or channels 7 the rivets 8 are enabled to hold or bind the riser plates with such stress that the resiliency of the plates is utilized to 40 press the side walls of said plates closely against the side walls of the grooves in the rails in which the plates are secured at all times and under all climatic variations, thus avoiding the separation of the riser plates 45 from the rails which would otherwise occur.

This invention materially prolongs the life of built up track crossings and switches, and is also of material advantage to motors, trucks and cars because it subjects them to 50 less shock in making the crossings. It is also of advantage to the crossing and switch foundations, because it reduces the shock in crossing and is easily repaired in case of excessive wear or damage to one or more of 55 the plates without the necessity of cutting the head of the rail or flange, as in the case of crossings in which the risers are formed integrally with the rails.

It will also be observed by reference to 60 the drawing that two of the crossing rails are continuous or through rails, and that only two of the rails are joined at the crossing. In case of replacement of any of the worn or damaged riser plates, it is unnecessary to take the crossing or switch out of 65

service or to remove the pavement of the street, as the repairs may conveniently be made without interrupting the traffic. The application of these renewable risers to built-up track crossings and switches attain the 70 full benefits and results derived from solid cast continuous riser crossing and switches at much less cost. Furthermore, the renewable riser sections may be applied to solid cast riser crossings and switches when 75 the latter have become worn or damaged in service. The application of these renewable riser plates in such cases may be attained by grinding or removing the surplus unnecessary metal from the worn crossings and 80 switches and applying the riser plates in the place thereof without removing the crossings castings or switches from the track.

There are numerous other advantages in addition to those mentioned which will be 85 readily apparent to those practically familiar with the difficulties of proper track construction for street railway lines. In practice the construction illustrated and described has been found greatly superior to 90 the usual structures which have been employed in an effort to attain the same results and advantages.

I claim:

1. A crossing, comprising intersecting 95 grooved rails, independently attachable and detachable riser plates seated within the grooves of the respective intersecting rails, having their upper surfaces in the same plane continuously between the gage lines 100 and arranged to serve as treads for the flanges of the car wheels passing the crossing; the end plates being tapered or inclined to prevent shock when the car wheels pass thereon and therefrom, and elements 105 binding said plates in position outside of the lines of contact of the wheel flanges.

2. A rail crossing, comprising intersecting grooved rails, manganese steel riser plates fitted within the grooves of the rails 110 continuously between the gage lines and having their upper surfaces in the same horizontal plane below the upper surfaces of the rails and arranged to serve as treads for the flanges of the car wheels passing the crossing, the end plates being inclined, and detachable elements binding said plates in position outside of the lines of contact of the wheel flanges. 115

3. A rail crossing, comprising intersecting flanged rails, riser plates secured upon the flanges of said rails and having grooves in their under sides, and having their upper surfaces below the upper surfaces of the rails, and detachable elements binding said 120 plates in position.

4. A rail crossing, comprising intersecting flanged rails, riser plates secured upon the flanges of said rails and having grooves in their under sides, and having their upper 125

surfaces below the upper surfaces of the rails and arranged to serve as treads for the flanges of the wheels passing the crossing, and detachable elements binding said plates in position outside of the lines of contact of the wheel flanges.

5. A rail crossing, comprising intersecting flanged rails, a riser plate secured upon the flange of each rail, one of said parts having a horizontal groove across which the other part extends, said riser plates having

their upper surfaces below the surfaces of the rails and arranged to serve as treads for the flanges of the wheels passing the crossing, and detachable elements binding said 15 plates in position outside of the lines of contact of the wheel flanges and passing through said grooves.

In witness whereof, I have signed this specification.

EDWIN D. SMITH.
